Specification for Design.

Patented July 26, 1921.

Application filed December 23, 1920. Serial No. 432,883. Term of patent 7 years.

To all whom it may concern:

Be it known that I, FREDERICK L. HAWKINS, a citizen of the United States, and a resident of Mishawaka, in the county of St. Joseph and State of Indiana, have invented a new, original, and ornamental Design for a Combined Shade and Curtain-Pole Bracket, of which the following is a specification, reference being had to the accompanying drawing, forming a part hereof.

Figure 1 is a side elevation of the bracket illustrating my new design.

Fig. 2 is an end view thereof.

Fig. 3 is a top or plan view thereof.

I claim:

The ornamental design for a combined shade and curtain pole bracket as shown.

In testimony whereof I affix my signature.

FREDERICK L. HAWKINS.
